CLAIM

We claim, the ornamental design for support plate for refrigerator container, as shown and described.

DESCRIPTION

FIG. 1 is the front perspective view of support plate for refrigerator container showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is an enlarged cross-sectional view taken through line A-A of FIG. 6;

FIG. 9 is an enlarged cross-sectional view taken through line B-B of FIG. 6; and,

FIG. 10 a front perspective view of the support plate for refrigerator container shown in an example environment.

The broken lines are for environmental purposes only and form no part of the claimed design.
